DESIGN FOR A CARTON

Morris Messing, New York, N. Y., assignor to Messing Bakeries Incorporated, Brooklyn,
N. Y., a corporation of New York

Application February 19, 1936, Serial No. 61,240

Term of patent 14 years

To all whom it may concern:

Be it known that I, Morris Messing, a citizen of the United States, residing at 242 E. 19th St., in the county of New York and State of New York, have invented a new, original, and ornamental Design for Cartons, of which the following is a specification, reference being had to the accompanying drawing, forming part thereof, in which

Fig. 1 is a perspective view of the complete carton showing my new design;

Fig. 2 is a top plan view taken from the opposite direction with respect to Fig. 1;

Fig. 3 is an elevational view of either side; and
Fig. 4 is an elevational view of either end.

I claim:

The ornamental design for a carton, as shown.

MORRIS MESSING.
